SPINNING TOYS

Albert E. Hartman, Washington, Kans.

Application May 19, 1954, Serial No. 430,824

1 Claim. (Cl. 46—71)

This invention relates to new and useful improvements and structural refinements in spinning toys, also commonly known as tops, and the principal object of the invention is to provide a toy of this nature having a novel arrangement of parts including a replaceable inertia head which may be quickly and easily removed for substitution by another.

Specifically, the invention concerns itself with a toy including a frame or yoke which functions as a handle for a rotatable spindle, one end of the latter being provided with a carrier in the form of a resilient clamp which is adapted to removably receive therein an inertia head, such as for example, a conventional can of shoe polish, the spindle also having a pull string wound thereon whereby rotation may be imparted thereto and to the associated head. As such, the invention readily lends itself to use with various different containers or other conventional articles as inertia heads and, by the same token, although not necessarily so, the invention may be used as a premiums to promote the sale of any such articles or products in the containers with which the invention is used.

Another feature of the invention resides in the provision of a fulcrum member on the spindle whereby the same, together with the associated yoke and inertia head may be rotatably supported upon a surface and permitted to spin freely thereon after the pull string has been actuated.

Other features of the invention reside in its simplicity of construction, convenient and entertaining operation, and in its adaptability to economical manufacture.

With the above more important objects and features in view and such other objects and features as may become apparent as this specification proceeds, the invention resides in the arrangement of parts and details of construction as shown in the accompanying drawing wherein like characters of reference are used to designate like parts and wherein:

Figure 1 is an elevational view of the invention;

Figure 2 is an edge view thereof, the inertia head being shown by dotted lines;

Figure 3 is a lower end view of the invention; and

Figure 4 is a perspective view of the carrier used therein.

With reference now to the accompanying drawing in detail, the spinning toy is designated generally by the numeral 10 and embodies in its construction a yoke or frame 12 which functions as a handle and consists of a pair of side pieces 14 connected at their upper and lower ends to a pair of axially aligned bearings 16, 18.

A shaft or spindle 20 is freely rotatable in the bearings 16, 18 and projects at both ends therefrom, the lower end of the spindle being provided with a substantially spherical fulcrum member 22.

2

The upper end of the spindle has secured thereto a carrier 24 which is in the form of a clamp having an elongated intermediate portion 26 provided at the underside thereof with an apertured boss 28 for attachment to the spindle.

An inertia head 30 of a disc-shaped configuration is removably positioned in the carrier 24, this being attained by engaging a pair of resilient end portions 32 of the carrier with a peripheral flange 34 with which the head 30 is equipped. For all practical purposes the head 30 may assume the form of a can of shoe polish, or the like, and it will be apparent from the foregoing that various other articles of a similar configuration may be selectively employed by substituting one for another. As is best shown in Figure 4, the end portions 32 of the carrier are preferably of an arcuate form, so that they are complementary to the contour of the head 30 and flange 34.

A pull cord 36 is wound around the spindle 20 as shown in Figure 1 so that by holding the yoke 12 and smartly pulling the cord 36, rapid rotation may be imparted to the spindle as well as the carrier 24 and head 30. When the cord is unwound from the spindle and the device is still in motion, it may be deposited in an upright position on a floor or some other supporting surface and the yoke 12, no longer held stationary, will gradually commence to spin until it eventually attains the speed of rotation of the spindle with the associated carrier and inertia head. In this respect, of course, the spherical member 22 will function as the fulcrum for the spinning action of the entire device.

While in the foregoing there has been shown and described the preferred embodiment of the invention, various modifications may become apparent to those skilled in the art to which the invention pertains. Accordingly, it is not desired to limit the scope of the invention to the foregoing disclosure and various changes and modifications may be resorted to such as may lie within the spirit and scope of the appended claim.

What is claimed as new is:

A spinning toy comprising in combination, a yoke affording a handle and consisting of a pair of strap-shaped arcuate side members disposed in coplanar relation, a pair of coaxial bearings provided integrally at the ends of said side members, a spindle rotatably mounted in said bearings and projecting at both ends from said yoke, a pull cord wound around the intermediate portion of said spindle in said yoke for imparting rotation to the spindle, a spherical fulcrum member provided on one end of the spindle whereby the same and the associated yoke may be sustained in a spinning position on a supporting surface, a carrier secured to the other end of said spindle and including a flat, continuous intermediate strap portion extending in opposite directions from said spindle and a pair of resilient clamp portions at the ends of said intermediate strap portion, and a disc-shaped circular head removably positioned in said carrier, said head having a flat bottom in supportable engagement with the flat intermediate portion of the carrier and a flanged perimetric wall frictionally engaged by said resilient clamp portions, said clamp portions being arcuate complementally to the perimetric wall of said head.
